Louis A. Mortimer.
by J. G. Roberts Atty.

UNITED STATES PATENT OFFICE.

LOUIS A. MORTIMER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,383,743.

Specification of Letters Patent.

Patented July 5, 1921.

Application filed August 24, 1918. Serial No. 251,206.

To all whom it may concern:

Be it known that I, LOUIS A. MORTIMER, a citizen of the United States, residing at New York, in the county of New York, State of New York, have invented certain new and useful Improvements in Telephone-Exchange Systems, of which the following is a full, clear, concise, and exact description.

This invention relates to telephone exchange systems and more particularly to those in which the telephone lines have terminals at a plurality of switchboards or stations.

In such system, especially those in which long distance or toll lines are employed, it is often desirable that switching centers or switchboards usually designated as through switchboards, for interconnecting such long distance lines, be located at stations, or 15 switchboards separate from those at which connections are made with the local lines, commonly called terminating switchboards, or those at which calls are originated over the line, commonly called outward switchboards. It is essential in cases of this nature that suitable signaling means be provided whereby the operator at one such switchboard may notify the operator at another switchboard when a call is to be handled by 20 the operator at the latter switchboard. However, due to the fact that the through switchboard is often located at a considerable distance from the terminating switchboard, it is also desirable to eliminate all 25 unnecessary conductors interconnecting such switchboards.

It is the object of this invention to provide a simple and inexpensive system of this nature in which the signaling between 30 certain switchboards, at which terminals of the line are located, is performed over the usual talking conductors of the line circuit, thus eliminating separate signaling conductors therebetween.

To attain this object, in accordance with a 35 feature of the invention, means associated with the talking conductors of the line circuit is provided at each switchboard which coöperate upon the receipt of an incoming 40 call to impress current of one polarity on the individual talking conductors and thereby cause the operation of the calling signal device at one switchboard and to simultaneously operate a busy signal at the other 45 switchboard.

In accordance with a second feature of the invention, operator-controlled means associated with the talking conductors of the line circuit is also provided at one switchboard to impress current of a different 60 polarity on the individual talking conductors of the line circuit and thereby cause the display of the calling signal at the other office in case the operator at the first switchboard wishes to transfer the call to such 65 switchboard.

In accordance with a third feature of the invention, means are provided whereby the subsequent recalling of the calling station upon the completion of the connection by 70 the operator at one switchboard may be accomplished over the talking conductors of the line without interfering with the signaling apparatus at the other switchboards.

These and other features not specifically 75 mentioned above will more fully appear from the following specification and the annexed drawing, in which the figure shows diagrammatically the terminus of a telephone line circuit associated with the various 80 classes of switchboards and embodying the invention, together with sufficient portions of a suitable associated connecting circuit to properly illustrate the invention.

In the accompanying drawing the transmission line, comprising conductors 1 and 2, is provided with jacks 46, 25 and 32 at the outward terminating and through switchboards X, Y and Z, respectively. At each of the switchboards a plurality of suitable 90 link circuits A is provided for connection with the jacks. Switchboard X is adapted for handling originating or outward calls and a calling signal lamp 44 is associated with jack 46 thereat by means of which calls 95 may be transferred thereto by the operator at switchboard Y. Switchboard Y is adapted for receiving incoming calls, which are indicated thereat by a calling signal lamp 22 associated with the jack 25. Switchboard Z 100 is adapted for handling through calls which may be transferred thereto by the operator at switchboard Y responsive to the actuation of the key 27 and indicated at switchboard Z by calling signal lamp 48. Signaling 105 lamps 10, 9 and 18 are provided at the switchboards X, Y and Z respectively, to indicate the busy condition of the transmission line when engaged in connection with any call.

It is thought that the invention may be more fully understood from the following description of the operation of the system shown on the drawing. Upon the receipt of 5 an incoming call, originated by the application of grounded alternating current to the conductors 1 and 2 at a distant station, not shown, relay 3 operates, causing the operation of relay 6, over a circuit extending from 10 battery, through the winding of relay 6 and the contact of relay 3 to ground. Relay 7 is operated over a circuit established from battery through the winding of relay 7 and the alternate contact of relay 6 to ground. 15 Relay 7 is thereupon locked in an operated position over a circuit extending from battery, through the winding and the right-hand inner alternate contact of relay 7 and the normal contact of relay 8 to ground. 20 Calling signal lamp 22 is lighted over a circuit extending from battery, through the left-hand outer alternate contact of relay 7, the left-hand normal contact of relay 23 and the lamp 22 to ground. Busy signal lamps 25 9 and 10 at switchboards Y and X respectively, are also lighted over a circuit established from battery, through the left-hand inner alternate contact of relay 7, the right-hand normal contact of relay 11 and the lamps 9 and 10 in multiple to ground. By 30 the closure of the right-hand outer alternate contact of relay 7, a circuit is completed from battery, through the right-hand outer alternate contact of relay 7, the upper winding of retardation coil 12, the tip conductor of the section of the line connecting switchboards Y and Z, the right-hand winding of retardation coil 13, the winding of polarized relay 14, the right-hand normal contact of 35 relay 15 and the winding of relay 16 to ground. Since relay 14 is unresponsive to the direction of flow of the current in this circuit such relay does not operate, although relay 16 operates, causing the operation of 40 relay 17, over a circuit established from battery, through the winding of relay 17 and the contact of relay 16 to ground. The closure of the right-hand contact of relay 17 causes the lighting of busy signal lamp 18 45 over a circuit extending from battery through the right-hand contact of relay 17 and the lamp 18 to ground. The closure of the left-hand contact of relay 17, completes a circuit from battery, through the left-hand contact of relay 17, the normal contact of 50 relay 5, the left-hand winding of retardation coil 13, the ring conductor of the section of transmission line joining switchboards Y and Z, the lower winding of retardation coil 55 12, the winding of retardation coil 19, the winding of relay 20 and the winding of relay 21 to ground. As in the case of the circuit traced for relay 14, the direction of current flow is such that relay 20 does not operate. However, relay 21 operates, causing 60 65

the operation of relay 11 over a circuit extending from battery, through the winding of relay 11 and the contact of relay 21 to ground. By the opening of its left-hand normal contact relay 11 opens the bridge 70 including relay 3, by closing its left-hand alternate contact completes the bridge including relay 4 and condenser 37, and by closing its right-hand alternate contact completes a circuit for busy signal lamps 9 and 10 from 75 battery, through the right-hand alternate contact of relay 11 and the lamps 9 and 10, in multiple, to ground, thereby replacing the former circuit for lamps 9 and 10, which was opened by the opening of the right-hand 80 normal contact of relay 11.

Although relay 5 is also normally bridged across the line in series with condenser 36, such relay is not responsive to the incoming ringing current operating relay 3, due to the 85 shunting effect of the grounded bridges, one of which includes the lower winding of coil 12 and its associated condenser and the other of which includes the condenser associated with the left-hand winding of coil 13, whereby relay 5 receives an insufficient amount of current to cause its operation. Although relay 4 may respond to such ringing current in case the application thereof is continued after the operation of relay 11, the 90 polarity of current thereby impressed upon the tip conductor leading to the switchboard Y agrees with that supplied to such conductor through the right-hand outer alternate contact of relay 7 so that the apparatus 95 associated with such tip conductor is unaffected by the operation of such relay.

The operator at switchboard Y, observing the lighted condition of lamp 22, inserts plug 24, of cord circuit A thereat, in jack 105 25, thereby operating relay 8 over a circuit extending from battery, through resistance 45, the sleeve contacts of plug 24 and jack 25, the right-hand normal contact of relay 23 and the winding of relay 8 to ground. 110 The opening of the normal contact of relay 8, opens the locking circuit of, and causes the release of relay 7. Although the opening of the right-hand outer alternate contact of relay 7 removes battery from the 115 circuit previously traced for relays 14 and 16, relay 16 is not released since battery of the same polarity is connected thereto through the normal contact of relay 26, the middle alternate contact of relay 8, and the 120 right-hand normal contact of relay 7. The busy signal lamp 18 is therefore maintained in a lighted condition. A locking circuit is also established for relay 11 from battery, through the winding of relay 11 and the left-hand alternate contact of relay 8 to ground. 125 The resistance 47 is provided to prevent momentarily short-circuiting the battery during the coincident operation of relays 7 and 11. Lamp 22 is extinguished by the 130

opening of the left-hand outer alternate contact of relay 7. Relay 29 is operated over a circuit established from battery, through the winding of relay 29 and the contact 30 of relay 8 to ground, thereby disconnecting the tip and ring conductors of the section of the transmission line joining switchboards Y and Z from the jack 25 and the conductors 1 and 2 of the transmission line. Relay 34 is also operated, due to the operation of relay 8, over a circuit established from battery, through the winding of relay 34 and the contact 31 of relay 8 to ground.

15 Although not shown on the drawing, since it is not essential to the proper understanding of the invention, the cord circuit A may be provided with any suitable form of switching arrangement whereby the operator's telephone set, also not shown, may be connected with such cord circuit.

Upon ascertaining that the connection desired, is such that the call should be handled by the operator at the through 25 switchboard Z, the operator at switchboard Y actuates the non-locking key 27, thereby operating relay 26 over a circuit established from battery, through the winding of relay 26 and the contact of key 27 to ground.

30 The opening of the normal contact of relay 26 removes the battery supply from the circuit including relays 14 and 16 and the closure of the left-hand alternate contact substitutes therefor a battery adapted to supply current of the opposite polarity. Such current operates relay 14, while 16 is maintained operated. Relay 28 is operated over a circuit extending from battery, through the winding of relay 28, and the 40 contact of relay 14 to ground. The closure of the left-hand alternate contact of relay 28, completes a locking circuit for such relay extending from battery, through the winding and the left-hand alternate contact of relay 28 and the middle normal contact of relay 15 to ground. Lamp 48 is

45 lighted over a circuit extending from battery, through the right-hand alternate contact of relay 28, the left-hand normal contact of relay 15 and the lamp 48 to ground. The opening of the middle normal contact of relay 28 opens the bridge including the condenser 36 and the relay 5.

50 When the operator at switchboard Z answers the transferred call by the insertion of plug 24 of a cord circuit A thereto into the jack 32, the relay 15 operates over a circuit from battery, through the resistance 45, the sleeve contacts of plug 24 and jack 32 and the winding of relay 15 to ground. By the opening of its left-hand normal contact, relay 15 extinguishes the lamp 48; by the opening of its middle normal contact it releases relay 28, thereby 55 reestablishing the bridge including con-

denser 36 and the relay 5; and by the closure of its left-hand alternate contact it completes a holding circuit for relay 17, from battery, through the winding of relay 17 and the left-hand alternate contact of relay 15 to ground. The opening of the right-hand normal contact and the subsequent closure of the right-hand alternate contact of relay 15 substitutes the winding of relay 33 for the winding of relay 16, in series with the winding of relay 14.

The operator at switchboard Y removes the plug 24, of the cord circuit A, thereat, from jack 25, thereby reestablishing the continuity of the line conductors from the 80 distant station to the switchboard Z, through the release of relays 8 and 29, as well as causing the release of relays 26, 14, and 34, but maintaining busy lamps 9 and 10 in a lighted condition due to the continued operation of relays 17, 21 and 11.

85 After the operator at switchboard Z has prepared the connection desired, it is the usual practice to signal the distant station on the transmission line, indicating that 90 the connection may be completed thereat, and the conversation may proceed. This is accomplished by the actuation of ringing key 35, in cord circuit A at switchboard Z, whereby relay 5 is operated over a circuit 95 established from the source of ringing current through the lower alternate contact of ringing key 35, the ring contacts of plug 24 and jack 32, the lower normal contact of relay 38, the right-hand normal contact of relay 28, the condenser 36, the winding of relay 5, the upper normal contact of relay 38, the tip contacts of jack 22 and plug 24 and the upper alternate contact of key 35 to ground. The operation of relay 5 105 changes the polarity of the current flowing through relays 20 and 21, thereby causing the operation of relay 20 while maintaining relay 21 in an operated condition. The operation of relay 20 causes the operation 110 of relay 29 over a circuit established from battery through the winding of relay 29 and the contact of relay 20 to ground. Relay 29, in operating, disconnects the tip and ring conductors of the section of the transmission line connecting switchboards Y and Z, from the line conductors 1 and 2 leading to the distant station, and connects a source of ringing current thereto, through the normal contacts of relay 34 and the alternate contacts of relay 29 to cause the operation 115 of a suitable signaling device at the distant station, not shown. Upon the release of ringing key 35, the responsive apparatus returns to its previous condition.

120 In case the distant station desires to rering the operator at switchboard Z, ringing current connected to the line conductors 1 and 2, at the distant station flowing through the lower normal contacts of relay 29, the left- 130

hand alternate contact of relay 11, the middle normal contact of relay 29, the condenser 37, the winding of relay 4, and the upper normal contact of relay 29 causes the operation of relay 4, thereby completing a circuit extending from battery, through the contact of relay 4 and the upper winding of retardation coil 12, the tip conductor of the section of the line connecting switchboards Y and Z, the right-hand winding of retardation coil 13, the winding of relay 14, the right-hand alternate contact of relay 15 and the winding of relay 33 to ground. Due to the direction of flow of current within such circuit, relay 14 does not operate, but relay 33 operates and causes the operation of relay 38, over a circuit completed from battery through the winding of relay 38, the left-hand normal contact of relay 28 and the contact of relay 33 to ground. Supervisory relay 39 in cord circuit A, is thereupon operated over a circuit established from the source of ringing current, through the lower alternate contact of relay 38, the ring contacts of jack 32 and plug 24, the lower normal contact of ringing key 35, the winding of relay 39, the upper normal contact of ringing key 35, the tip contacts of plug 24 and jack 32 and the upper alternate contact of relay 38 to ground. Supervisory lamp 40 is lighted over a circuit established from battery, through the lamp 40 and the contact of relay 39 to ground, thereby signaling the operator at switchboard Z.

In case the operator at switchboard Y in answering the incoming call finds that the nature of the desired connection is such that it should be handled through the outward switchboard X, which is usually located closely adjacent to the switchboard Y, the call may be transferred thereto by the actuation of key 41, thereby operating relay 23, over a circuit established from battery, through the winding of relay 23 and the contact of key 41 to ground. Relay 7 operates over a circuit established from battery, through the winding of relay 7, the normal contact of relay 6, contacts 42 and 43 of relay 23 and the contact of key 41 to ground. Lamp 44 at switchboard X is lighted over a circuit established from battery, through the left-hand outer alternate contact of relay 7, the left-hand alternate contact of relay 23 and the lamp 44 to ground. Relay 8 is released, due to the opening of the right-hand normal contact of relay 23, thereby locking relay 7, over a circuit extending from battery, through the winding and the right-hand inner alternate contact of relay 7 and the normal contact of relay 8 to ground.

The busy signal lamp 18 is maintained in a lighted condition and relays 16, 17, 21 and 11 are maintained in an operated condition

as previously described in connection with 65 the original operation of relay 7.

The operator at switchboard Y removes the plug 24, of cord circuit A, thereat, from the jack 25, and the operator at switchboard X answers the transferred call by the insertion of the plug 24, of a cord circuit A, at such switchboard into jack 46, whereupon relay 8 operates over a circuit extending from battery, through resistance 45, the sleeve contacts of plug 24, and jack 46 and 75 the winding of relay 8 to ground. Lamp 44 is extinguished, due to the release of relay 7 caused by the opening of the normal contact of relay 8, and the other subsequent operations depending upon the operation of 80 relay 8, result as previously described in connection with the answering of the incoming call at switchboard Y.

It will thus be seen that by means of this invention the talking conductors of the section of the transmission line which interconnects two widely separated switchboards, may be employed for the signaling incident to the transferring of an incoming call from one switchboard to the other switchboard 90 and that effective means is also provided for relaying the signaling current past the retardation coils present in such section of the transmission line.

What is claimed is:

1. A telephone exchange system comprising a transmission line circuit, a plurality of switchboards connected thereto, a calling signal at one of the switchboards, signal control means thereat responsive to signaling current on the line, a busy signal at another of the switchboards, means controlled by the signal control means for impressing a current on one of the talking conductors of the line interconnecting the 100 switchboards, and means at the second mentioned switchboard responsive thereto for operating the busy signal device.

2. A telephone exchange system comprising a telephone line, a plurality of switchboards connected thereto, signal control means at one of the switchboards responsive to signaling current on the telephone line, a calling signal device controlled thereby, 110 a plurality of sources of current of different polarities, means controlled by the signal control means for connecting one source of current at said one of the switchboards to one line conductor interconnecting such switchboard and another switchboard, signal control means at the second mentioned switchboard responsive thereto, a busy signaling device at the second mentioned switchboard controlled by the signal control means thereat, switching means at the first 115 mentioned switchboard for substituting another source of current for the first mentioned source to impress current of a different 120 source to the second mentioned switchboard, and 125 means for connecting the second mentioned switchboard to the telephone line.

polarity upon the line conductor, means at the second mentioned switchboard responsive thereto and a signal device thereat operated thereby.

- 5 3. A telephone exchange system comprising a telephone line, a plurality of switchboards connected thereto, a calling signal device at one of the switchboards, a busy signaling device at another of the switchboards, another signaling device at the second mentioned switchboard, a plurality of sources of current of different polarities at the first mentioned switchboard, signal control means thereat controlling a calling signaling device, operator-controlled means at the first mentioned switchboard for isolating the section of line circuit extending therefrom to the second mentioned switchboard, switching means responsive to the operation 15 of the signal control means to connect one of said sources to one conductor of the isolated section, signal control means at the second mentioned switchboard responsive to current from any of said sources connected to such 20 conductor to operate the busy signaling device, additional operator-controlled switching means at the first mentioned switchboard to selectively connect another of said sources to the conductor, and signal control means 25 at the second mentioned switchboard responsive thereto to operate the second mentioned signaling device thereat.
4. A telephone exchange system comprising a telephone line, a plurality of switchboards connected thereto, a calling signaling device at one of the switchboards, a busy signaling device at another of the switchboards, a plurality of sources of current of different polarities at the first mentioned 30 switchboard, means responsive to signaling current on the line to operate both signaling

devices, said means including one of the sources of current, operator-controlled means at the first mentioned switchboard to substitute for such source another source of 45 current having a different polarity, and another signaling device at the second switchboard responsive thereto.

- 5 5. A telephone exchange system comprising a telephone line, a plurality of switchboards connected thereto, signal control means at one of the switchboards responsive to periodically varying current flowing through the line conductors in *seriatim*, switching means responsive thereto to connect a source of current to an isolated conductor of the line circuit extending to another of the switchboards, a signaling device at the second mentioned switchboard responsive thereto, a link circuit at the second-mentioned switchboard for connection with the line and means responsive to the connection of the link circuit with the line for maintaining the signaling device in operated condition independent of the signal-control 55 means.

6. A telephone exchange system comprising a telephone line, a plurality of switchboards connected thereto at one end thereof, operator-controlled means at one of the 70 switchboards for isolating the portion of the line extending to another of the switchboards, a source of current at the first mentioned switchboard, additional operator-controlled means thereat for connecting the 75 source of current to one conductor of the isolated portion of the line, and a signaling device at the second mentioned switchboard responsive thereto.

In witness whereof, I hereunto subscribe 80 my name this 19th day of August, A. D. 1918.

LOUIS A. MORTIMER.
